UNITED STATES PATENT OFFICE.

THOMAS F. I. O'BRIEN, OF BROOKLYN, NEW YORK.

CLOSURE FOR RECEPPILES.

Application filed October 21, 1920. Serial No. 418,473.

To all whom it may concern:

Be it known that I, THOMAS F. I. O'BRIEN, a citizen of the United States, residing at Brooklyn, in the county of Kings 5 and State of New York, have invented certain new and useful Improvements in Closures for Receptacles; and I do hereby declare the following to be a full, clear, and exact description of the invention, such 10 as will enable others skilled in the art to which it appertains to make and use the same.

This invention relates more particularly to receptacle closures such as are applied 15 to bottles and jars, etc., and is of the type which may be removed and replaced at will.

The objects of the invention are to provide a receptacle closure of this type which will be secure, but which may be readily 20 manipulated both to apply and remove it; to obtain a structure which will resist internal pressure from the container; to provide a structure adapted to various sizes and makes of containers; to employ parts 25 which may be readily manufactured with minimum operation and material; to positively hold the cap in place; to prevent the parts from becoming separated; to secure simplicity of construction and manipulation, and to obtain other advantages and 30 results as may be brought out in the following description.

Referring to the accompanying drawing in which like numerals of reference indicate similar parts throughout the several 35 views;

Figure 1 is a perspective view of my improved closure in operative position upon a bottle;

Figure 2 is a perspective view showing the closure removed from the bottle;

Figure 3 is a cross sectional view of the same taken upon a diametric plane through the middle of an opposite pair of jaws, and

Figure 4 is a perspective view of the invention as applied to a jar.

In the specific embodiment of the invention illustrated in said drawing the reference numeral 1 indicates in general the receptacle closure, which comprises a top or body 2 around the circumference of which are depending jaws 3 adapted to be clamped inwardly by means of a ring 4. As shown in Figure 1 the receptacle closure is adapted to be positioned upon the bottle 5, the bottle having a downwardly facing shoul-

der 6 near its mouth as is common with bottles now upon the market. The closure is proportioned so as to overlie the mouth of the bottle and with its jaws 3 substantially the same length as the distance of said shoulder from the mouth of the bottle. In other words, the jaws 3 will depend to substantially the plane of said shoulder 6. As shown clearly in Figures 1 to 3 the jaws 65 are provided with inturned lips 7 on their lower ends adapted to underlie said shoulder and prevent the closure from coming off of the bottle. Preferably jaws 3 are of resilient metal so they will normally 70 spread apart or open as shown in Figures 2 and 3 to permit the closure to be applied to or removed from the bottle. After the closure is applied the ring 4 is slid downwardly, pressing the jaws toward each 75 other and causing the lips 7 to engage under the shoulder 6. So long as the ring remains slid down the closure will be very securely held against withdrawal, but obviously the user may very readily slide the 80 ring upwardly and then remove the closure without difficulty.

In order to prevent the ring from being slid off the jaws, I have shown tabs or ears 8 projecting outwardly from the body 2 at 85 intervals around the same far enough to overlie the ring and engage the same when it is pushed up to that position, as clearly shown in Figure 2. By preference these tabs or ears 8 are formed from metal in 90 the plane of the body 2 between the jaws 3, and in this way the entire cap may be made of one piece of material stamped out with a minimum number of operations and thus are not only easily manufactured but are 95 also cheaply manufactured because of the minimum operations and material, and also have maximum strength and durability.

If it is found desirable the jaws 3 may have wedge like protuberances 9 near their 100 bottom ends, said protuberances being arranged and adapted to be engaged by the ring 4 as it is pressed down which will accordingly exert greater inward pressure upon the jaws for securely clamping them 105 toward the receptacle. It may also be noted that these protuberances also serve an additional function in that they more positively prevent the ring 4 from being slid down so far as to come off the jaws, 110 although it will be understood that the tendency of the jaws to spread apart is

ordinarily sufficient to keep the ring from coming off.

It is to be understood that the present invention may be constructed of various shapes and in various sizes and for cylindrical shaped receptacles it is preferable to have the closure conformed of similar shape and for that reason the jaws 3 have been shown curved and the lips 7 similarly curved at their inner edges to obtain engagement upon the shoulder 6 for their entire length. It is to be understood, however, that this may be varied and the cap made otherwise in this respect without departing from the spirit or scope of the present invention.

Obviously, for larger receptacles a greater number of jaws may be employed, and for purposes of illustration the invention has been shown applied in Figure 4 to an open mouthed jar or jelly glass 10, the closure being otherwise substantially as described except for the increase of size and also the increase in number of jaws. Other detail modifications and changes may be made in the manufacture and use of my in-

vention, and I do not wish to be understood as restricting myself except as recited in the following claim when construed in the light of the prior art.

Having thus described my invention, I claim:—

A closure for bottles or the like comprising a circular body member having a plurality of radially extending legs, alternate legs being relatively long with respect to those next adjacent, the relatively short legs lying in the same plane with the body, the relatively long legs being bent adjacent the circumference of the body part into planes oblique to the body and being provided adjacent their outer ends with outwardly projecting cam parts and inwardly directed gripping parts, and a ring member surrounding said relatively long legs and between said relatively short legs and said cam parts, substantially as specified.

In testimony whereof I affix my signature.

THOMAS F. I. O'BRIEN.
